US0D1076291S

(12) United States Design Patent (10) Patent No.: US D1,076,291 S
(45) Date of Patent: * May 20, 2025

(54) CLEANING WAND

(71) Applicant: Henkel AG & Co. KGaA, Duesseldorf (DE)

(72) Inventors: Glenn William Kaye, Norwalk, CT (US); Peter Brian Clarke, Newton, CT (US); Luis Ramiro Gutierrez Montenegro, Stamford, CT (US); John Kevin Clay, Milford, CT (US); Daniel Peter Sterling, Fairfield, CT (US)

(73) Assignee: Henkel AG & Co. KGaA, Duesseldorf (DE)

() Term: 15 Years

(21) Appl. No.: 29/816,578

(22) Filed: Nov. 23, 2021

(51) LOC (15) Cl. 15-05

(52) U.S. Cl.

USPC D32/15; D4/138

(58) Field of Classification Search

USPC D32/17, 25, 34, 39, 40, 42, 51, 52; D4/138, 199; D8/80, 81, 83, 107, 300; D23/223

CPC A47K 11/10; A47K 13/10; A47K 17/00; A47L 13/254

See application file for complete search history.

(57) CLAIM

The ornamental design for a cleaning wand as shown and described.

DESCRIPTION

FIG. 1 is a front view of a cleaning wand showing the claimed design;

FIG. 2 is a rear view thereof;

FIG. 3 is a left side view thereof;

FIG. 4 is a right side view thereof;

FIG. 5 is a top view thereof; and,

FIG. 6 is a bottom view thereof.

The dashed broken lines in the figures show portions of the cleaning wand that form no part of the claimed design.

1 Claim, 3 Drawing Sheets
